UNITED STATES PATENT OFFICE.

JOHN A. WESER, OF NEW YORK, N. Y.

MUSICAL INSTRUMENT.

SPECIFICATION forming part of Letters Patent No. 793,335, dated June 27, 1905.

Application filed January 16, 1905. Serial No. 241,167.

To all whom it may concern:

Be it known that I, JOHN A. WESER, a citizen of the United States, residing in the borough of Manhattan, in the city of New York, in the State of New York, have invented certain new and useful Improvements in Musical Instruments, of which the following is a specification, reference being had to the accompanying drawings, forming a part thereof.

10 This invention relates to automatic musical instruments, such as automatic pianos and organs and automatic players, and is particularly concerned with the operative connections between the mechanically-controlled actuating devices and the action of the instrument, such as the ordinary hammer-operating devices of a piano. In musical instruments of the class referred to such operative connections are generally complicated with a multiplicity of levers and connecting-rods, and, as is well understood, great care is necessary in the assembling of such parts in order that the proper adjustment may be secured.

It is the object of this invention to simplify such connections and at the same time to provide for the ready and convenient adjustment of each connection.

The invention will be more fully explained hereinafter with reference to the accompanying drawings, in which for purposes of explanation and illustration of the nature of the invention it is shown as embodied in a convenient and practical form.

In the drawings, Figure 1 is a sectional view showing enough of an ordinary piano-action to illustrate the application of the present invention thereto. Fig. 2 is a detail view, on a larger scale, illustrating particularly the manner of securing the adjustable finger to the pneumatic. Figs. 3 and 4 are detail views illustrating modifications in the arrangement of the adjustable finger of the pneumatic.

The invention is illustrated in the drawings as applied to an upright, automatic piano in which the power-pneumatics may be controlled by any usual means, not necessary to be described or shown in detail herein.

The parts which are more or less directly involved with the present improvements are sufficiently shown in Fig. 1 and comprise, as usual, a key-lever *a*, pivoted upon the key-base in the usual manner and adapted to engage the usual abstract *b*. The latter is pivotally connected at its upper end to a rocker *c*, which carries a trigger or jack *d*, arranged to operate the hammer *e*, as usual, the string with which the hammer co-operates being indicated at *f*. The mechanical devices or pneumatics for actuating the hammers are preferably located above the key-levers *a*, two of such pneumatics being represented at *g*. The pneumatics may be of any suitable construction and may each comprise, as usual, a valve-box *h*, connected by a tube *i* with the usual tracker-board, a wind-trunk *k*, and a main or power pneumatic or bellows *l*, having a movable board or member *m*.

In instruments of this class as heretofore constructed it is usual to provide the movable member *m* of the power-pneumatic with a rigid projecting finger, which is connected by a system of links and levers with the abstract. In the present case, however, all of such intermediate links and levers are dispensed with, and each abstract is provided with a shoulder which may be conveniently formed by gluing a block *n* upon the abstract, and the movable board or member *m* of each power-pneumatic is provided with a pivoted or rocking adjustable finger *o*, arranged to engage the block or shoulder *n*. As shown clearly in Fig. 2, this adjustable finger is thickened at its middle part, as at *p*, to form a fulcrum-point to bear against the movable board *m* of the power-pneumatic and is held in place by a screw *q*, which passes loosely through a hole *r* in the finger *o* and enters the movable board of the pneumatic. At the outer end of the movable board of the pneumatic, in a position in which it is convenient of access, is secured a threaded stud *s*, which enters a slot *t* in the end of the finger *o* and receives between the finger *o* and the bottom board *m* a suitable nut *u*. A spring *w* may be applied

between the movable board *m* and the other end of the finger *o* to press the forward end of the finger against the nut *u* and prevent rattling. It will now be understood that when 5 the power-pneumatic *l* is collapsed the rear end of the finger *o* directly engages the block or shoulder *n* on the abstract *b* and causes the hammer *e* to be actuated in the usual manner. Furthermore, by rotation of the nut *u* 10 upon the threaded stud *s* the rear end of the finger *o* is adjusted to accommodate the position of the block *n* upon the abstract. In this manner the adjustment of the pneumatics to the piano-action is readily and quickly accomplished, and special care in the location of the blocks upon the abstracts is rendered unnecessary.

In Fig. 2 of the drawings the spring *w* is shown as located between the inner end of the 20 finger *o* and the bellows-board *m*; but obviously it may be located between the outer end of such finger and the bellows-board, as shown in Fig. 3, in which case the nut *u* is located on the stud *s* outside of the finger *o*. In this 25 arrangement the spring *w* may be employed, if desired, to modify the tone of the instrument, stiffer or weaker springs being employed, as may be desired. The springs obviously may be arranged to coöperate with 30 the fingers in any convenient manner, or, if desired, they may be dispensed with altogether, as indicated in Fig. 4, in which two nuts *u* are shown as threaded upon the stud *s* to receive the end of the finger between them. 35 As will be seen upon reference to Fig. 1 of the drawings, the improved connection between the pneumatics and the abstracts permits an exceedingly compact arrangement of the pneumatics with reference to one another 40 and to the piano-action to be attained. The pneumatics, arranged in tiers, can be accommodated to the space requirements of modern pianos, and scarcely more room is required in a piano which can be used both manually 45 and mechanically than would be required in a piano to be used either manually or mechanically alone. Furthermore, the direct connection of the pneumatic to the abstract permits the requisite movement of the pneumatic 50 to be only about two-thirds of what would be necessary if the pneumatic acted directly upon the front end of the key, as in manual playing. The shorter required movement of the pneumatic and its correspondingly quicker 55 movement renders the action of the pneumatic more powerful and improves the quality of the tone.

It will be understood that the form of the 60 adjustable finger, as well as the means for securing it to the pneumatic and the means for effecting adjustment thereof, may be varied to suit different conditions of use and that the in-

vention is not to be restricted to the precise construction shown and described herein.

I claim as my invention—

1. In an automatic musical instrument, the combination of a power-pneumatic and a piano-action comprising an abstract, of a lever movably secured to the pneumatic and operating directly on the abstract and means to adjust 70 said lever with relation to the pneumatic, said lever moving in concert with the pneumatic and the abstract, substantially as described.

2. In an automatic musical instrument, the combination with a piano-action comprising a 75 series of abstracts, tiers of power-pneumatics arranged in proximity to said abstracts, levers movably secured to said pneumatics and directly engaging said abstracts, and spring-tension devices applied to said levers.

3. In an automatic musical instrument, the combination with a power-pneumatic and playing devices to be actuated thereby, of a fulcrumed lever secured to said pneumatic and adapted to engage said playing devices, a 85 spring to coöperate with said lever, and a regulating device to coöperate with said lever in opposition to said spring.

4. In an automatic musical instrument, the combination with a power-pneumatic and playing devices to be actuated thereby, of a pivoted or rocking finger carried by the movable 90 member of said pneumatic and in operative relation with said playing devices, and means to adjust said finger, substantially as described.

5. In an automatic musical instrument, the combination with a power-pneumatic and a piano-action comprising an abstract, of a pivoted or rocking finger carried by the movable member of said pneumatic and in operative 100 relation with said abstract, and means to adjust said finger, substantially as described.

6. In an automatic musical instrument, the combination with a power-pneumatic and a piano-action comprising an abstract, of a finger fulcrumed upon the power-pneumatic and adapted to engage said abstract, and means to adjust 105 said finger, substantially as described.

7. In an automatic musical instrument, the combination with a power-pneumatic and a piano-action comprising an abstract, of a finger fulcrumed upon said pneumatic and adapted to engage said abstract, a threaded stud secured to said pneumatic, and a nut upon said stud to engage said finger, substantially as 115 described.

8. In an automatic musical instrument, the combination with a power-pneumatic and playing devices to be actuated thereby, of a rocking finger carried by the movable member of 120 said pneumatic and in operative relation with said playing devices, a regulating and tone-modifying spring between the outer end of said finger and said movable member, and a

stop to coöperate with said finger and limit the action of said spring, substantially as described.

9. In an automatic musical instrument, the combination with a power-pneumatic and playing devices to be actuated thereby, of a movable regulating-lever carried by and with the movable member of said pneumatic and in op-

erative relation with said playing devices, substantially as described.

This specification signed and witnessed this 12th day January, A. D. 1905.

JOHN A. WESER.
